UNITED STATES PATENT OFFICE.

CHARLES E. EDGAR, OF PARSONS, KANSAS, ASSIGNOR TO THE EDGAR MANUFACTURING COMPANY, OF KANSAS CITY, MISSOURI, A CORPORATION OF MISSOURI.

REFRIGERATOR.

No. 880,867.

Specification of Letters Patent.

Patented March 3, 1908.

Application filed June 25, 1906. Serial No. 323,285.

To all whom it may concern:

Be it known that I, CHARLES E. EDGAR, a citizen of the United States, residing at Parsons, in the county of Labette and State of Kansas, have invented certain new and useful Improvements in Refrigerators, of which the following is a specification.

My invention relates in general to a refrigerator and is designed especially for one that is to be used in hotels, theaters, residences, refrigerator cars, etc., in connection with a central plant or supply station that furnishes the refrigerant.

The objects of my invention are to construct a simple apparatus of this character operating without frost or dampness outside of the machine and adapted to control the temperature, humidity and circulation of air within the chamber in which it is placed; and it consists in the main of an outer casing inclosing a refrigerating surface, a tank for the refrigerant, a valve for controlling the flow of the refrigerant within the tank, and a vertical shaft within the casing provided with an air fan at one end and a rotary pump at the other end which force air and brine, respectively, over the refrigerating surface; the air fan also entraining air through an opening in the top of the casing and blowing the air from within the casing out through a series of apertures disposed substantially at the bottom thereof.

Particular attention is called to the construction of the float in the valve, it being open at its bottom end so that it has the same pressure on the inside as the outside except the small pressure due to the height of the liquid from the bottom edge of the float to the liquid level within, which permits a float to be used of exceedingly light construction as there is always gas rising under it that buoyes it up when the device is in operation.

In the drawings Figure 1 is a vertical section of my device; Fig. 2 is a cross-section on the line 2—2 of Fig. 1; Fig. 3 is a cross-section on the line 3—3 of Fig. 1; and Fig. 4 is an enlarged vertical section of the valve.

Referring now more particularly to the drawings, 5 represents the casing inclosing the tank 6, which latter affords a refrigerating surface and receives the refrigerant through the supply pipe 7 connected to the central plant, the gases that form within the tank 6 passing out through the pipe 8 connected therewith. The tank is provided

with an extension refrigerating surface 9 in the form of an annular chamber which is secured to and communicates with the bottom of the tank, while its lower end is closed and secured to the casing 10 of a centrifugal pump hereinafter described. Coiled about the tank and its extension is a pipe 11, one end of which communicates with the tank at 12 while the other end communicates with the lower portion of the extension tank at 13, and within this pipe is a refrigerant, forming an additional refrigerating surface.

Secured within the casing and seated upon the angle irons 14 secured thereto is the brine reservoir 15, adapted to contain brine or the like and within which is the casing 10 of the centrifugal pump, having an opening 16 into a pipe 20 and secured to said brine reservoir by means of the lugs 17, said casing 10 inclosing a centrifugal pump piston designated 75 as a whole at 18, that is rotated by a vertical shaft 19 supported by a pipe 20 communicating with the brine tank and serving as a discharge pipe for the brine. The discharge pipe 20 is attached at its top by 80 means of collar 21 to an electric motor, designated as a whole at 22, to which the shaft is connected by suitable means, and at the top end of the shaft above the motor I provide a fan 23 to entrain the air from the chamber through an opening 24 in the casing 5 and drive it downward through the casing, around the refrigerating surface and out through the openings 25, annularly disposed around the casing near its bottom end. 90

As a means for filling the brine tank I provide the same with a downwardly extending pipe 53 to which a valve 54, of the ordinary form, is secured and adapted to be coupled with a hose or the like for the purpose of 95 filling the tank. The pipe is arranged to extend downwardly in order that the tank may be easily drained, as well as for the reason that the pipe becomes frosted during the operation of the machine, causing moisture to accumulate thereon which will be caught in the overflow tank. 100

26 is the controlling means for the motor.

To confine the brine as closely as possible to the refrigerating surface I provide the top 105 of the tank 6 with the serrations 27 and the annular flange 28 which extends out substantially even with the coiled pipe so that the flow of brine is checked and distributed evenly over the upper surface of the tank as 110

it is forced through the apertures 29 in the discharge pipe. Furthermore, I provide the interior of the casing with conical shaped baffle plates 30 and 31 so disposed as to deflect all the brine that may splatter from the coil back upon it again whereupon it will fall into the brine reservoir. An overflow reservoir 32 is disposed below an opening 33 in the bottom of the casing 5 to catch any brine splattered over the edge of the brine reservoir or caused by brine absorbing dampness from the air as it passes through the machine.

Referring now to the valve mechanism in detail, shown in Figs. 3 and 4, 34 is a casing provided with a chamber 35 with which the supply pipe 7 communicates and is provided with a plug 36 adapted to be screwed into the casing 34 for the purpose of conveniently reaching the valve in case it is desired to remove the same. Within said chamber is the valve cage 37 provided with a stem 38 adapted to be screwed into the casing of the chamber, said cage having apertures 39 communicating with the chamber and a movable cap 40 secured to the cage by a through pin 41; said cap having a groove 42 in its upper surface in order that it may be removed by a screw driver or the like after the through pin is removed. The stem is axially bored, as shown at 43, to communicate with the refrigerating tank and valve cage and adapted to receive a valve stem 44 which operates the ball valve 45 within the cage. A float lever 46, one end of which is connected to the valve stem and is fulcrumed at 47, is provided with the jaws 48 connected to the float 49 by the links 50 which are pivoted to the jaws and to the lugs 51 on the float. The float is provided with an open bottom and an apertured top, and in the preferred form I encircle the aperture with a depending annular flange 52. The discharge pipe passes through the apertured end of said float and the annular flange so as to form a guide for the float when it rises or falls. The flange, however, may be omitted if desired, as the aperture may be so constructed as to permit a free sliding movement of the float on the discharge pipe without the escape of any gas therethrough. By constructing the float open at its bottom end the gases from the refrigerant fill the space between the upper surface of the liquid in the float and the top of the float which buoys it up and consequently permits a much lighter float to be used.

The device operates as follows: The refrigerant from the main supply tank (not shown) passes through the pipe 7 into the chamber 35, through the valve and into the tank 6, extension tank 9 and pipe 11, the quantity of the refrigerant being regulated by the valve, and the pipe 8 affording means for the passage of the gas out of the tank.

At any desired time the motor is set in operation whereupon the centrifugal pump forces the brine in the brine tank up through the discharge pipe and out through the apertures therein whereupon it runs from the top surface of the tank around the serrations and down over the pipe 11, tank 6 and its extension; the baffle plates in this instance serving to keep the brine in contact with the refrigerating surface and to direct it back to the brine tank. And to further prevent a condensation or frost forming upon the refrigerating surfaces I provide the fan 23 which entrains the air from the pipe in the top of the casing 5 and carries it down through said casing and out the apertures 25, the baffle plates in this instance preventing any brine from being carried out of the casing by the forced air. Thus the fan has two functions, besides operating conjointly with the centrifugal pump; namely, in forcing the cold air within the casing out into the chamber, and also entraining the free air from within the chamber, thus producing a circulation of air within the room or chamber in which the refrigerator is situated.

Having now described my invention, and wishing it understood that I do not confine myself to the precise details of construction what I claim is:

1. In a refrigerator, the combination of a casing provided with ports for the intake and exit of air, a refrigerant tank and a brine tank within the casing, a shaft, a tube inclosing the shaft and communicating with the brine tank, a fan at one end of the shaft and a centrifugal pump at its other end, ports in said tube, and means for rotating said shaft, substantially as described.

2. In a refrigerator, the combination of a casing provided with an aperture at its top and a series of ports near its bottom, a refrigerant tank within said casing, valve controlled means for admitting the refrigerant within the tank, a coil of pipe encircling said tank and coöperating therewith at both ends, a brine tank below said coil of pipe, a vertically disposed discharge pipe communicating with said brine tank and provided with apertures positioned above said coil of pipe, a shaft within said discharge pipe, a centrifugal pump at the lower end of said shaft and within said brine tank, a fan at the other end of said shaft, and means for turning said shaft, substantially as described.

3. In a refrigerator, the combination of a casing, a reservoir within said casing, valve-controlled means for supplying said reservoir with a refrigerant, a coil of pipes surrounding and communicating with said reservoir, a motor within said casing, a shaft for said motor, an air-fan and a centrifugal pump on said shaft, a brine reservoir, said pump being in communication with said brine reservoir whereby when said shaft is rotated by said

motor said liquid is discharged about said reservoir and coil of pipe and the atmosphere within said casing is circulated downward for the purposes described.

- 5 4. In a refrigerator, the combination of a casing, a reservoir and a motor within said casing, valve-controlled means for supplying said reservoir with a refrigerant liquid, a pipe communicating with said reservoir and
10 adapted to carry away the gases therefrom, a shaft for said motor, an air fan and a centrifugal pump on said shaft arranged above and below said motor, respectively, apertures

in said casing for the intake and exit of air, a series of baffle plates arranged between said apertures, means for supplying brine to said centrifugal pump, whereby when said shaft is rotated brine is discharged upon said reservoir for the purpose of preventing frost from accumulating thereon and air is circulated within said casing, substantially as and for the purposes described. 15 20
